Hochstrasser & Maffson,

Door Spring.

N° 8,704.

Patented Feb. 3, 1852.

Inventors:

Henry Hochstrasser

Abraham Maffson

UNITED STATES PATENT OFFICE.

HY. HOCHSTRASSER AND A. MASSON, OF PHILADELPHIA, PENNSYLVANIA.

DOOR-SPRING.

Specification of Letters Patent No. 8,704, dated February 3, 1852.

To all whom it may concern:

Be it known that we, HENRY HOCHSTRASSER and ABRAHAM MASSON, of the city and county Philadelphia, State of Pennsylvania, have invented a new and Improved Door-Spring for the Purpose of Closing Doors by the Power of Said Spring; and we hereby declare that the following is an exact description thereof, reference being had to the accompanying drawings and to the letters of reference marked thereon.

The nature of our invention consists of the application of a curve (to be fastened 15 to the door-frame in such position as hereafter described) to and in connection with a spring with rollers attached to one end, which end moves in and on the curve, for the purpose of having the spring act more 20 powerfully on the door when about shut than when open; the other end of the spring to be placed in an iron on the door; which iron can be permanent or movable as may be preferred. Although the spring may have 25 its greatest tension when the door is open, it acts with less power because the end of the spring with the rollers attached is by the action of opening the door thrown in toward the center of the hinges or axis of 30 the door; and in and by the action of closing the door, the same end of spring moving in the curve is thrown out from the center of the hinges or axis of the door, causing the spring to act more powerful. Al- 35 though the tension of the spring is lessened, because it is then a considerable distance from and back of the center of the hinges, or axis of the door. To explain more fully: If a spring of the kind here described 40 should have one end placed directly on a line with the hinges or door-frame, and the other end attached to the door, it is evident that it would work precisely the same and with the door; but if you attach the spring 45 out of the line, either out from or back of the center of the hinges, the spring will meet with resistance and will assume an elliptic form, and its tension or power will tend to close the door; now if we can throw 50 the spring out from the center, by the action of the door when it is closed or closing, and in toward the center when opening, we have the greatest power when closed or nearly so, and the lesser power when open. This arrangement has the following 55 advantages, viz: 1st. Persons passing in or

out, usually leave the door partly open, and the springs now in use will not close it, or if made of sufficient power, it will be so great as to shatter the door. 2nd. This 60 spring can be put on any part of a door, which does not require to be thrown back farther than a right angle with the door-frame, either on top at midway or at the bottom of the door—if on top it can be 65 thrown back farther. 3rd. It can be taken off and put on with little trouble. 4th. Its durability—as it cannot lose its elasticity like a coil or spiral spring. 5th. Its com- 70 parative freedom from friction and noise.

To enable others skilled in the art to make and use our invention, we will proceed to describe its construction and operation.

We construct our spring of tempered 75 steel, flat and straight in shape (other shapes will do) of width to suit the opening or division in the curve, its thickness and length will be proportioned to the size of the door and power required. On one end 80 of the spring we turn an eye in which we insert a pin, on each end of the pin we fasten a roller with a groove turned therein, for the purpose of preventing them from slipping out of the curve. 85

The above described spring is shown in sectional drawing A. The curve we make of metal of form similar to sectional drawing D, having an opening or division in its center to admit the passage of the spring as in perspective drawing I. We place the curve on the door frame, so that the center of the lower or inner part of the curve (see sectional drawing D, Figure 2) or the center of the rollers when in that part of the curve will be about a quarter of an inch back and from the center of the hinge or axis of the door if the hinge projects out farther than usual, then block the curve out so as said center will be on a line with the center of hinges as above described. After 90 the curve is secured as above shut the door and place the end of the spring with the rollers attached in and on the outer part of the curve. The other end of the spring 95 place in the iron or rack attached to the door for that purpose which rack is shown in sectional drawing G, which can be used for the purpose or some similar device, which can be placed at one-half or three-quarters of the width of the door distant 100 from the center of the hinge or axis of the 105 door.

door, the length of the spring to be made to correspond, which must be one-eighth of an inch longer than its bearing place on the rack, at most not more than one-quarter of an inch as the more the spring is bowed or approaches the elliptic form, the less power it exerts when the door is closed. Now when the curve and spring is placed as above and as shown in the drawing E and the door is closed the spring exerts its greatest power or nearly so, because the end in the curve stands out farther from and back of the center of the hinges or axis of the door than when the door is open. In opening the door a short distance, which distance can be regulated by the shape of the outer part of the curve, the end of the spring in the curve, moves in the curve toward the center of the hinge or axis of the door (as shown in sectional drawing F) which lessens the power of the spring be-

cause it is nearer the center or axis of the door.

We do not claim the straight piece of steel for a spring as new, neither do we ²⁵ claim having the spring act most powerful when the door is closed, as new.

What we do claim as new and our invention or improvement and desire to secure by Letters-Patent, is—³⁰

The application and mechanical arrangement of a curve in connection and combination with a spring and rollers for the purpose of a door spring—whose power will be exerted more strongly when the door is closed or about closed, than when open entirely or partially as herein described.
